CLAIM

The ornamental design for a hook set for hook assembly for a tackle box, as shown.

DESCRIPTION

FIG. 1 is an isometric view of a hook assembly for a tackle box insert showing my new design;

FIG. 2 is an enlarged side elevational view thereof;

FIG. 3 is a right side view thereof;

FIG. 4 is a back view thereof;

FIG. 5 is a front view thereof;

FIG. 6 is a top view thereof; and,

FIG. 7 is a bottom view thereof.

The broken lines showing the hook support are for the purposes of illustrating environment and form no part of the claimed design.
